TRANSFORMER PROTECTIVE SWITCH

Filed July 2, 1928

Inventor:
Wilbur K. Dickinson,
by *Charles E. Mullar*
His Attorney.

UNITED STATES PATENT OFFICE

WILBUR K. DICKINSON, OF LYNN, MASSACHUSETTS, ASSIGNOR TO GENERAL ELECTRIC COMPANY, A CORPORATION OF NEW YORK

TRANSFORMER PROTECTIVE SWITCH

Application filed July 2, 1928. Serial No. 289,730.

The present invention relates to transformers and while it is not limited thereto necessarily, it finds especial utility in connection with current transformers. For this reason the invention is here illustrated and described as applied to a current transformer.

The object of the invention is to provide in connection with a transformer such as a current transformer, an improved protective device for protecting the windings of the transformer from overloads, and for a consideration of what I believe to be novel and my invention, attention is directed to the accompanying description and the claims appended thereto.

Referring to the drawing, Fig. 1 is a perspective view of a current transformer provided with a protective device embodying my invention, and Fig. 2 is a diagrammatic view illustrating the circuit arrangement.

Referring to the drawing, 5 indicates a current transformer of suitable construction provided with a primary winding 6 and a secondary winding 7. 8 and 9 indicate the two terminals of the primary winding. In Fig. 2, 10 indicates a measuring instrument connected to the secondary winding of the transformer. The arrangement illustrated is to be taken as typical of any suitable transformer construction.

According to my invention I provide a conductor 11 associated with the primary winding 6 of the transformer and adapted to be connected in shunt with the primary winding in case of overload on the transformer, the arrangement being such that conductor 11 is automatically connected in shunt to the primary winding upon the occurrence of an overload and is, in the present instance, automatically disconnected as soon as the overload subsides. According to the embodiment of the invention illustrated in the drawing, I connect one end of conductor 11 to primary winding terminal 8 and I connect the other end to a contact 12, which forms the stationary contact of a circuit closer. In the present instance, contact 12 forms a continuation of and is a part of

conductor 11 which with advantage may be in the form of a flat bar.

The movable contact of the circuit closer comprises a flat bar 13 carried by and forming a part of the armature 14 of an electromagnet. Contact 13 and armature 14 are carried by a frame 15 provided with guides 16 which slide on vertical posts 17 mounted on a base plate 18 which in turn is carried by a suitable support 19 formed of insulating material. The upper ends of posts 17 are connected by a cross bar 20. 21 indicates vertically-adjustable stops on posts 17 which serve to limit upward movement of frame 15. Frame 15 is normally biased into engagement with stops 21 by a spring 22 connected to cross piece 20. Contact 13 is connected by bolts 23 to arms 24 which form a part of frame 15, the bolts passing loosely through holes in the arms and being provided with wing nuts on their outer ends. Surrounding bolts 23 between arms 24 and conductor clamps 25 are springs 23^a which serve to yieldingly hold contact 13 in the position shown in Fig. 1 of the drawing. The compression of springs 23^a may be adjusted by means of the wing nuts. The arrangement serves to permit contact 13 to move against the action of springs 23^a when it is forced into engagement with stationary contact 12. Mounted on base 18 is a laminated structure 26 which forms the core of the electromagnet. The face of the laminated structure is provided with a transversely extending groove in which is located a straight, flat bar 27 which forms the winding of the electromagnet. At its one end, bar 27 is connected to terminal 9 of the primary winding and at its other end is connected to the circuit conductor 28. Contact 12 is carried by a body 29 of insulation which rests on bar 27. Movable contact 13 is electrically connected to bar 27 by suitable connectors 30. In the present instance, connectors 30 are shown as being in the form of flexible circular bands clamped to contact 13 by the clamps 25 and clamped to bar 27 by suitable clamps 31. In Fig. 1, the left hand connector 30 is broken away in order to show certain parts more clearly.

The protective device is connected in series with the transformer as is illustrated in the drawing. Normally spring 22 holds contact 13 in its uppermost position and out of engagement with contact 12. The spring is 5 adjusted so that for normal loads on the transformer the electromagnet does not exert sufficient pull on contact 13 and armature 14 to bring contact 13 into engagement with contact 12. When a predetermined overload 10 occurs on the transformer, however, the electromagnet pulls contact 13 down into engagement with contact 12 thus connecting bar 11 in shunt to primary winding 6. The 15 impedance of the shunt circuit formed by bar 11 is much lower than that of the transformer winding so that now most of the current is shunted around the primary winding of the transformer by means of the bar 20 thereby protecting the transformer from the overload. However, there remains a sufficient amount of current passing through the primary of the transformer so that the secondary will deliver enough current to operate such relays or other protective devices 25 as may be connected with it.

I have found that a protective device of this type when properly designed after the manner disclosed in the drawing can be 30 made to operate in a small fraction of a second and with ample speed to readily protect the transformer. For example the protective device may be made to operate with a speed of the order of one-thousandth 35 (1/1000) of a second.

As soon as the current decreases again below the predetermined high value, spring 22 serves automatically to lift contact 13 from engagement with contact 12 thus opening 40 the shunt circuit. With this arrangement, it will be seen that the operation of the protective device is entirely automatic in both directions. This is an important feature of the invention since it means that the 45 protective device requires no attention on the part of an operative and no manual resetting.

When desirable, I may provide in connection with the electromagnetic circuit closer, 50 a second circuit closer which is closed whenever the electromagnetic circuit closer is closed and which functions to open a suitable circuit breaker such as an oil circuit breaker in the main circuit of the transformer primary. This arrangement may be used in combination with an overload relay 55 in the secondary circuit of the transformer.

32 indicates a contact carried by the movable frame 15 and adapted, when the frame 60 moves downward, to bridge a pair of contacts 33. Contacts 33 are connected to the trip coil 34 of a circuit breaker 35 located in the main lead of the primary transformer winding 6. With this arrangement it will 65 be seen that whenever the electromagnetic

circuit closer moves downward to bring contact 13 into engagement with contact 12, contact 32 bridges contacts 33, thereby effecting the opening of the circuit breaker 35.

In the circuit of the secondary transformer 70 winding is an overload relay 36 which, when actuated, closes a circuit on trip coil 34 to effect opening of circuit breaker 35. Overload relay 36 may be set to operate at a load somewhat lower than that at which the electromagnetically-operated protective circuit closer operates. Ordinarily it will be a slower acting piece of mechanism than the electromagnetically-operated circuit closer. In the case of a short circuit, for example, 80 the electromagnetically-operated circuit closer would function to connect conductor 11 in shunt to the primary transformer winding and open switch 35 before the overload relay 36 would operate. 85

As stated above, my invention possesses especial utility in connection with current transformers. Heretofore it has been the practice and has been found necessary to make current transformers of a sufficiently 90 large size to withstand the overloads met with. As a result, they have been much larger than have been necessary for normal operation. This has added materially to their size and cost. By my invention I am 95 enabled to reduce very materially the size of current transformers for a particular application, being able to reduce them in size by an amount of the order of two-thirds. 100 As a result the current transformer with its protective device are together not as large as the current transformer alone prior to the application of my invention. The result is a saving in cost and size of the instruments. 105

In accordance with the provisions of the patent statutes I have described the principle of operation of my invention, together with the apparatus which I now consider to represent the best embodiment thereof, but I 110 desire to have it understood that the apparatus shown is only illustrative and that the invention may be carried out by other means.

What I claim as new and desire to secure by Letters Patent of the United States, is: 115

1. An electro-magnetically operated circuit closer for use as a protective device comprising a stationary magnetic core structure having a transverse slot, a bar which extends through said slot and forms the winding of an electromagnet, a contact carried by and insulated from said bar, a movable contact structure which forms the armature of the electromagnet, and flexible conductors connecting the movable contact structure to said bar. 120

2. An electro-magnetically operated circuit closer for use as a protective device comprising a stationary magnetic core structure, a movable magnetic core structure, and a 130

current carrying conductor and two contacts extending between said core structures, one of said contacts being connected to said movable core structure to be moved thereby 5 toward and from said other contact, and a conductive connection between said movable contact and said conductor.

3. An electro-magnetically operated circuit closer for use as a protective device comprising a stationary magnetic core structure, a movable magnetic core structure, and a current carrying conductor and two contacts extending between said core structures, said conductor and one of said contacts being 10 stationary, the other of said contacts being movable, said stationary contact extending between said conductor and said movable contact, said movable contact being connected to said movable core structure to be 15 moved thereby toward and from said stationary contact, and a conductive connection between said movable contact and said conductor.

In witness whereof, I have hereunto set 25 my hand this 27th day of June, 1928.

WILBUR K. DICKINSON.
